(57) **CLAIM**

The ornamental design for an exercise apparatus as shown and described.

DESCRIPTION

FIG. 1 is a front perspective view of our new design of an exercise apparatus;

FIG. 2 is a front view of the design of FIG. 1;

FIG. 3 is a rear view of the design of FIG. 1;

FIG. 4 is a side view of the design of FIG. 1; and,

FIG. 5 is a top view of the design of FIG. 1.

The broken lines in FIGS. 1 through 5 illustrate features that form no part of the claimed design of the exercise apparatus.
